(57) **CLAIM**

The ornamental design for a flooring tile having drainage holes, as shown and described.

DESCRIPTION

FIG. 1 is a top plan view of a flooring tile having drainage holes, according to an embodiment of the invention; and, FIG. 2 is a side view of the flooring tile having drainage holes of FIG. 1.

The dash-dot-dash lines illustrate unclaimed boundary lines and form no part of the claimed design. The dashed lines illustrate environmental subject matter that forms no part of the claimed design. Thickness forms no part of the claimed design.

1 Claim, 2 Drawing Sheets

FIG. 1

FIG. 2
